UNITED STATES PATENT OFFICE.

DANIEL S. WAUGH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,114,949.

Specification of Letters Patent. Patented Oct. 27, 1914.

Application filed April 20, 1914. Serial No. 833,116.

To all whom it may concern:

Be it known that I, DANIEL S. WAUGH, a citizen of the United States, residing at Denver, in the county of Denver and State of Colorado, have invented new and useful Improvements in Rock-Drills, of which the following is a specification.

The present invention relates to rock drills, and more particularly those of the 10 type employing a valveless motor.

One of the primary objects of the present invention is to provide a practical structure in which a relatively large amount of air is contained within the machine so as to provide 15 a reservoir of motive fluid from which the supply for actuating the motor is taken.

Another and important object is to provide a structure of this type in which a relatively large body of motive fluid will act 20 upon the piston during the working stroke. This is particularly useful where a relatively low air pressure is employed and the expansion of the air is utilized in the operation of the machine.

25 An embodiment of the invention that has proven entirely satisfactory, is disclosed in the accompanying drawings, wherein:—

Figure 1 is a side elevation of the machine. Fig. 2 is a longitudinal sectional view therethrough. Fig. 3 is a cross sectional view. Fig. 4 is a detail sectional view on the line 5—5' of Fig. 3. Fig. 5 is a view similar to Fig. 4, but showing the 30 valve in closed position. Fig. 6 is a detail 35 sectional view on the line 7—7' of Fig. 3.

Fig. 7 is a view similar to Fig. 7, but showing the valve in closed position. Fig. 8 is a view in elevation of the cylinder body or barrel, a portion thereof being broken away. 40 Fig. 9 is a longitudinal sectional view therethrough. Fig. 10 is an end elevation. Fig. 11 is a cross sectional view. Fig. 12 is a cross sectional view. Fig. 13 is a detail perspective view of parts of the feed piston, portions being broken away. Fig. 14 is a detail perspective view of the reservoir element with a portion broken away. Fig. 15 is a similar 45 view of the plug element.

Similar reference numerals designate corresponding parts in all the figures of the drawings.

In the embodiment disclosed, a valveless motor, designated generally by the reference numeral 17, is employed, to the rear

end of which is connected the feeding 55 means 18.

The motor 17 comprises a cylinder formed of a barrel or body 19, having a front piston chamber 20 of relatively great diameter. In the rear portion of this piston chamber, 60 are opposite internal enlargements forming reservoir pockets 21. Located in the rear end of this barrel 19, just in the rear of the said pockets 21, is a plug element 22, having a central longitudinal open-ended piston 65 chamber 23 of less diameter than the piston chamber 20. This plug has a peripheral flange 24 that abuts against the rear end of the barrel 19 and is clamped in position by a head block 25 that also bears against the 70 rear end of the barrel 19. This head block has an internal tapered bore 26, in which is snugly fitted the tapered end 27 of a reservoir element and partition wall, comprising a shell having an internal chamber 28 75 of greater area than the piston chamber 23 and in constant communication with the rear end of the same. This chamber 28 constitutes a constant pressure chamber from which the motive fluid is distributed, 80 and into and out of which the rear end of the smaller piston head moves without interfering with the inlet ends of the distributing ports therein.

Operating in the cylinder member, is a 85 piston comprising a large front head 29 that is located in the piston chamber 20, and a smaller and longer rear head 30 that operates in the smaller piston chamber 23 and is movable back into the chamber 28, the 90 two heads being connected by a reduced neck portion 31, which in effect forms an annular groove 32. Motive fluid is supplied from the reservoir 28 to the rear portion of the front larger piston chamber 20 behind 95 the head 29, through the medium of ports 33, which are formed in the plug 22, opening through the rear end thereof, and into the front portion of the smaller piston chamber 23, where they are uncovered by 100 the annular groove 32 when the piston moves rearwardly. Other ports or passages 34 lead from the rear portion of the piston chamber 23 outwardly through the plug 22, thence longitudinally in the cylinder 105 barrel and open into the front end of the piston chamber 20 in advance of the head 29. Exhaust passageways 35 are

formed in the cylinder barrel 19 and have inlet ports 36 opening through the walls of said cylinder barrel into the piston chamber 20, the head 29 passing on opposite sides of these ports.

5 The piston head 29 operates against a tappet 37 suitably mounted in the front head 38 of the motor, said tappet, in turn, operating against the rear end of a drill-bit 39 detachably supported in a chuck sleeve 40 carried by the head 38.

For the purpose of moving the motor to its work and holding it in operative position, the feeding means 18 is employed. In 15 the particular embodiment disclosed, this feeding means comprises a cylinder 41 having a flanged head 42 that abuts against the rear face of the head block 25, and also against a flange 43 formed upon the reservoir shell 27. A collar 44, surrounding the feed cylinder 41, and bearing against the flange 42, has passed therethrough the side bolts 45, which also pass through ears 46 formed on the front head 38. The parts are 20 thus held together by these side bolts.

25 Operating in the feed cylinder 18, is a piston which includes a head 47 threaded upon a piston rod 48 that projects through a plug 49 suitably secured in the rear end of the cylinder 41. The outer end of this piston rod 48 is formed into a spur 50. Located upon the inner end of the head 47, are packing cups 51 having a washer 52 interposed between them, the outer cup also having a 30 washer 53 located therein. These parts are all held against rotation by being mounted on pins 54 carried by the head 47, and they are held to said head by a cap screw 55 that passes through the various parts, and is 35 threaded into the head.

40 Expansible motive fluid is supplied to the machine from any suitable source, through a hose 56 connected, as shown more particularly in Fig. 3, to a nipple 57 that is 45 threaded into an enlargement 58 formed upon one side of the head block 25. This enlargement is provided with a tapered valve seat 59 formed at the inner end of the nipple 57, and in the valve seat is rotatably 50 mounted a tapered throttle valve 60 projecting from the head block on the side opposite the nipple, said projecting end having a suitable operating handle 61. The larger end of the throttle valve 60 is recessed, as 55 shown at 61, and is thus in communication with the nipple. Leading from this recess, as shown in Figs. 6 and 7, is a large port 62, and one or more smaller ports 63 that are 60 respectively movable into and out of register with a port or passage 64, which communicates with the front end of the feed cylinder 41 in advance of the feed piston. It will thus be evident that by turning the 65 valve, the motive fluid must be entirely cut off from the feed cylinder, as shown in Fig.

7, and by rotating the valve, first the smaller port 63 will be brought into register with the port 64, then the larger port, and finally the full size port 62. Motive fluid can thus be slowly introduced into the feeding means 70 to bring the motor slowly to its work.

The motive fluid is conducted from the feed cylinder into the reservoir 28, and for this purpose, the enlargement 58 of the head block 25 is provided with a pair of 75 convergently disposed ports 65 that open, respectively, into the feed cylinder and the reservoir, and also open through the valve seat 59. The throttle valve 60 has a passageway 66 that communicates with both 80 ports 65 when the port 62 is in communication with the port 64. As a consequence, the motive fluid will first enter the feeding means 18 and pass thence into the reservoir 28. The supply of motive fluid to the feed- 85 means and to the motor, is, however, controlled by the single throttle valve 60. For the purpose of turning the machine, a handle 67 is mounted on the side of the head block opposite the throttle valve, and this 90 handle is made tubular, forming a lubricant reservoir 68 that communicates with the interior of the machine.

Briefly described, the operation is substantially as follows:—The spur 50, having 95 been placed against a rock or other support, air is first slowly admitted to the feed bar by turning the valve 60, so that the machine is brought up to the work. The throttle valve is then turned to fully open position, 100 and the motive fluid will flow into the feeding means, and thence into the reservoir chamber 28. Constant pressure of the motive fluid is thus against the rear end of the smaller piston head 30, and said head fur- 105 thermore constitutes means for controlling the distribution of this motive fluid from the reservoir to the piston chamber 20 on opposite sides of the larger head 29. For example, assuming the parts in the position shown 110 in Fig. 2, the exhaust passages 35—36 are open in rear of the head 29, and the head 30 is far enough forward to expose the passage 34, so that the motive fluid will pass from the reservoir 28 into the piston chamber 115 20 in advance of the piston head 29. The piston will thus be driven rearwardly. The exhaust ports 36 will, however, be quickly closed, so that the motive fluid behind the head 29 will be compressed. In 120 like manner, the port 34 will be quickly closed by the rear head 30 and the continued rearward movement of the piston depends upon the expansion of the motive fluid in advance of the head 29. This con- 125 tinues until the head 29 has passed the exhaust port 36, whereupon the motive fluid will exhaust in advance of the head 29. By this time, the annular groove 32, formed by the neck 31 which connects the two piston 130

heads 29 and 30, will have uncovered the ports 33. The motive fluid will thus flow from the reservoir 28, through said groove 32, into the piston chamber 20, behind the head 29. The pressure against the rear face of the front head 29, assisted by the pressure against the rear head 30 will drive the piston forward on its working stroke, and this stroke will continue even after the ports 33 are closed by the head 30 because of the expansion of the motive fluid in the chamber 20 behind the head 29. In this connection, it will be noted that the pockets 21 are always in rear of the head 29 and afford material additional space for motive fluid, so that a relatively large body of the same will be in a position to act against the rear face of the head 29. This has been found especially advantageous where there is a low pressure air supply available, and materially increases the drilling capacity of the machine.

From the foregoing, it is thought that the construction, operation, and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new and desire to secure by Letters Patent, is:

1. In apparatus of the character set forth, the combination with a cylinder member having a front piston chamber of relatively large diameter, a rear piston chamber of smaller diameter communicating with the front chamber and an enlarged constant pressure chamber in rear of the rear piston chamber of greater diameter than the same and communicating therewith, of a piston comprising a front head operating in the front piston chamber, a rear head operating in the rear chamber and a reduced neck portion connecting the pistons, means for supplying motive fluid to the enlarged constant pressure chamber and thereby maintaining a constant pressure therein and against the rear end of the smaller piston head, and ports leading from the enlarged constant pressure chamber and controlled by the piston of smaller diameter for delivering motive fluid from the enlarged pressure chamber to the front piston chamber on opposite sides of the enlarged piston head therein.

2. In apparatus of the character set forth, the combination with a cylinder member having a front piston chamber of relatively large diameter, a rear piston chamber of smaller diameter communicating with the front chamber and an enlarged constant

pressure chamber in rear of the rear piston chamber of greater diameter than the same and communicating therewith, of a piston comprising a front head operating in the front piston chamber, a rear head operating in the rear chamber and a reduced neck portion connecting the pistons, means for supplying motive fluid to the enlarged constant pressure chamber and thereby maintaining a constant pressure therein and against the rear end of the smaller piston head, and ports leading from the enlarged constant pressure chamber and controlled by the piston of smaller diameter for delivering motive fluid from the enlarged pressure chamber to the front piston chamber on opposite sides of the enlarged piston head therein, the rear end of said smaller piston entering the enlarged constant pressure chamber in spaced relation to the walls thereof and to the inlet ends of certain of said ports.

3. In apparatus of the character set forth, a valveless motor, comprising in combination, a cylinder member having a rear piston chamber of relatively small diameter and a front piston chamber of greater diameter, a piston in the cylinder member having portions of different diameters operating respectively in the different chambers, a motive fluid reservoir in rear of the smaller piston chamber of greater diameter than the same and having constant communication with the rear end thereof, means for supplying motive fluid to the reservoir and thereby maintaining constant pressure against the rear end of the piston, and means controlled by the portion of the piston operating in the smaller piston chamber for distributing motive fluid from the reservoir to the larger piston chamber on opposite sides of the portion of the piston operating therein.

4. In apparatus of the character set forth, a valveless motor, comprising in combination, a cylinder member having a body provided with a plurality of piston chambers of different diameters and a rear head block mounted on the body and having an enlarged reservoir in constant communication with the rear piston chamber, a piston in the cylinder member having portions of different diameters operating respectively in the different chambers, one of said portions being movable into and out of the reservoir, means for supplying motive fluid to the reservoir, and means controlled by the movements of the piston for distributing the motive fluid to cause the operation of said piston.

5. In apparatus of the character set forth, a valveless motor, comprising in combination a cylinder body having an enlarged front piston chamber, a plug detachably fitted in the rear end of the body and hav-

- ing a smaller piston chamber, and a head block secured to the rear end of the cylinder body and having a motive fluid reservoir communicating with the rear end of the 5 smaller piston chamber, a piston operating in the cylinder and having portions of different diameters located respectively in the piston chambers, means for supplying motive fluid to the cylinder member, and distributing ports controlled by the portion of 10 the piston operating in the smaller piston chamber for distributing the motive fluid from the reservoir to the larger piston chamber on opposite sides of the portion of 15 the piston therein.
6. In apparatus of the character set forth, the combination with a cylinder member having a piston chamber, of a piston having a portion operating in the piston chamber, said piston chamber having a reservoir pocket that opens solely thereinto, the open portion being located always in rear of the portion of the piston operating in the said piston chamber, and means for delivering 20 motive fluid into the piston chamber to operate the piston, said motive fluid periodically filling the piston chamber behind the piston and also the pocket to form a relatively large body of fluid behind said piston 25 on its working stroke.
7. In apparatus of the character set forth, the combination with a cylinder member having a piston chamber, of a piston having a portion operating in the piston chamber, said piston chamber having a plurality of reservoir pockets that open solely thereinto, the open portions being located always in rear of the portion of the piston operating in said piston chamber, and means separate 30 from the pockets for delivering motive fluid into the piston chamber to operate the piston, said motive fluid periodically filling the piston chamber behind the piston and also filling the pockets to form a relatively large 35 body of fluid behind said piston on its working stroke.
8. In apparatus of the character described, the combination with a cylinder member having a front large piston chamber and a rear smaller piston chamber, said larger piston chamber having in its rear portion an internal enlargement forming a reservoir pocket, of a piston having portions of different diameters operating respectively 40 in the piston chambers, the larger portion being disposed at all times in advance of the pocket, and means for distributing motive fluid to the larger piston chamber.
9. In apparatus of the character described, 45 the combination with a cylinder member having a front large piston chamber provided in its rear portion with internal enlargements forming reservoir pockets, of a plug located in rear of the enlargements and having a smaller piston chamber, and a piston 50 operating in the cylinder member and having portions of different diameters operating respectively in the different chambers, said cylinder member and plug having ports controlled by the portion of the piston operating in the smaller piston chamber for distributing motive fluid to the larger piston chamber on opposite sides of the portion of the piston operating therein, said portion 55 operating in advance of the pockets.
10. In apparatus of the character set forth, the combination with a cylinder member having a front piston chamber of relatively large diameter and a rear piston chamber of smaller diameter communicating with the front chamber, of a piston comprising a front head operating in the front piston chamber and a smaller rear head operating in the rear chamber, said front piston chamber having a reservoir pocket that opens solely thereinto, the open portion being located in rear of the enlarged piston head operating in said piston chamber, and means controlled by the smaller piston head for delivering motive fluid into the front piston chamber in rear of the large piston head, said motive fluid periodically filling the piston chamber behind the enlarged piston head and also filling the pocket to form a relatively large body of fluid behind said piston 60 head on its working stroke.
11. In apparatus of the character set forth, the combination with a valveless motor, including a cylinder member having piston chambers of different diameters, of a head block for the rear end of the cylinder member having an enlarged reservoir in constant communication with the rear piston chamber, a piston having portions of different diameters operating respectively in the piston chambers, said cylinder member having ports for distributing motive fluid to the forward piston chamber on opposite sides of the portion of the piston operating therein, said ports being controlled by the portion 65 of the piston operating in the rear piston chamber, feeding means connected to the head block and comprising a cylinder and a piston operating therein, means for delivering motive fluid through the head block into the feeding means and for directing it from said feeding means into the reservoir, and a throttle valve located in one side of the head block for controlling both the supply of motive fluid to the feeding means and its passage from said feeding means into the reservoir.
12. In apparatus of the character described, a motor including a cylinder having a piston chamber provided with a lateral enlargement forming a reservoir pocket that is freely open into the rear portion of the piston chamber, a piston member operating in the chamber and being always disposed in advance of the open end of the pocket, and

means for delivering motive fluid into the piston chamber to operate the piston, said motive fluid periodically filling the piston chamber behind the piston and also the pocket, to form a relatively large body of fluid.

In testimony whereof I have hereunto set

my hand in presence of two subscribing witnesses.
